UNITED STATES PATENT OFFICE.

RICHARD H. BATE, JR., OF CONSHOHOCKEN, PENNSYLVANIA.

BOILER-FLUE CLEANER.

1,116,366.

Specification of Letters Patent. Patented Nov. 10, 1914.

Application filed November 20, 1913. Serial No. 802,103.

To all whom it may concern:

Be it known that I, RICHARD H. BATE, Jr., a citizen of the United States, residing at Conshohocken, in the county of Montgomery and State of Pennsylvania, have invented new and useful Improvements in Boiler-Flue Cleaners, of which the following is a specification.

My invention relates to new and useful improvements in boiler flue cleaners, and has for its object to provide an exceedingly simple and effective device of this character, which may be placed within the inclosing walls and in front of the boiler flues or tubes, whereby the steam within the flue cleaner may be super-heated or completely dried before it is discharged into the flues, whereby the soot, scale and other foreign matter may be readily blown from the flues without the possibility of wetting said foreign matter which causes it to bake on the flues.

A still further object of the invention is to provide a discharge pipe or header having a number of valves therein which control the supply of steam to a number of distributing pipes from which lead branch pipes, both the distributing pipes and branch pipes having nozzles which are located at points opposite the ends of the flues.

A still further object of the invention is to provide a single discharge pipe or header connected with a supply pipe, the flow of steam to the discharge pipe being regulated by a valve, and to provide a series of nozzles connected in sets with the header, the supply of steam to each set being regulated by a spring actuated valve, each of which is operated by a separate flexible cable, such as a chain.

A still further object of the invention is to provide a nozzle for my improved flue cleaner, whereby the steam will be given a whirling motion as it enters the flues, so that the foreign matter may be readily removed.

With these ends in view, this invention consists in the details of construction and combination of elements hereinafter set forth and then specifically designated by the claims.

In order that those skilled in the art to which this invention appertains may understand how to make and use the same, I will describe its construction in detail, referring

by numeral to the accompanying drawing forming a part of this specification, in which—

Figure 1, is a front elevation of a boiler showing my improved boiler flue applied thereto, a portion of the front wall and doors being broken away to clearly illustrate the construction. Fig. 2, is a vertical longitudinal sectional view thereof. Fig. 3, 60 is an enlarged side elevation of one of the nozzles. Fig. 4, is a longitudinal sectional view thereof. Fig. 5, is an end view thereof; and Fig. 6, is a section at the line 6—6 of Fig. 3. Fig. 7 is a side elevation of one of 65 the distributing pipes with its various branches, and the nozzles attached thereto. Fig. 8, is a longitudinal sectional view of a 70 spring actuated valve; and Fig. 9, is a section at the line 9—9 of Fig. 8, looking in 75 the direction of the arrow.

In carrying out my invention as here embodied 2 represents a boiler having flues or tubes 3 therein.

4 denotes my improved boiler flue cleaner 80 which is mounted in front of the boiler within the inclosing walls, so that the steam therein may be super-heated or dried before passing into the flues, but is of such construction that the draft is not interfered with. Leading from the boiler 2 is a steam supply pipe 5 which is connected with the discharge pipe or header 6, and has a valve 7 situated therein to regulate the supply of the steam to said header. From said supply pipe between the valve 7 and the boiler 2 leads a drain pipe 8, the ends of which preferably passes through the inclosing walls and enters the ash pit, whereby the water may be drained from the supply pipe before the 90 steam is turned into the header and said drain pipe has a valve 9 situated therein for opening and closing the same.

The discharge pipe or header 6 has connected thereto a number of valves 10, each of which is provided with a spring actuated valve stem 11 carrying a rotatable valve plug 27 having a plurality of openings 28 which when the valve is open are adapted to align with similar openings 29 in the valve seat 30. The spring 31 which actuates the stem 11 through the medium of the valve plug 27 is placed within the body of the valve and one end attached to the body of the valve while the other end is attached to the valve plug as plainly shown in Fig. 8, and from each of these valves leads a dis-

tributing pipe 13 having branch pipes 14 connected thereto. The distributing pipes and their branch pipes carry a number of nozzles 15, one of which is opposite each of the flues 3 of the boiler and each distributing pipe with its branch pipe and nozzles forms a section which is controlled by one of the valves 10. On the outer end of each of the spring actuated valve stems 11 of the 10 valve stem is mounted a grooved wheel 12 or its equivalent and to each of these is connected a flexible cable 16 such as a chain which run over the sheaves 17 situated within the inclosing walls and mounted 15 upon a bracket 18 carried by the front wall 19 and then over other sheaves 20 mounted at right angles to the first named sheaves and journaled in the bracket 21, secured to the outer face of the front wall 19, the 20 chains passing through suitable openings in said front wall and to the outer ends of said chains are fastened the handles 22. The nozzles 15 each comprise a threaded 25 stem 23, whereby they may be secured to the distributing pipes and branch pipes and a body 24 having a plurality of spiral openings 25 passing longitudinally therethrough, which will impart a whirling motion to the steam as it enters the flues, so that the foreign matter may be readily removed.

The operation of the device is as follows: The valve 9 is first open and the water drains from the supply pipe 5 through the drain pipe 8, after which the valve 9 is 35 again closed and the valve 7 in the supply pipe 5 opened, which permits the steam to enter the discharge pipe or header 6 where it is allowed to remain a short time so that the temperature will completely dry 40 the steam or cause it to be super-heated. By pulling upon one of the flexible cables 16, the wheel 12 to which said cable is connected will be rotated against the action of the spring actuated valve stem 11, thus opening 45 the valve and permitting the steam to pass into the distributing pipe 13, then into the branch pipes and through all of the nozzles of one section and into the flues opposite to which the nozzles are situated, thus 50 cleaning a number of the boiler flues without interfering with the remaining flues. Because of the whirling motion imparted to the steam as it enters the flues the foreign matter will be virtually scraped from the 55 interior faces of the flues and carried along with the jets of steam and out of the opposite ends.

Of course I do not wish to be limited to the exact details of construction as herein shown, as these may be varied within the 60 limits of the appended claims without departing from the spirit of my invention.

Having thus fully described my invention, what I claim as new and useful, is—

1. In a boiler flue cleaner a discharge pipe 65 or header connected with a boiler, a number of valves situated in said discharge pipe, a distributing pipe leading from each of said valves, branch pipes leading from the distributing pipes and nozzles carried by the 70 distributing pipes and branch pipes and located at points opposite the ends of the flues to be cleaned.

2. In a boiler flue cleaner a discharge pipe 75 or header located within the inclosing walls and in front of the boiler, a plurality of 80 spring actuated valves situated within the discharge pipe, means for operating said valves, a supply pipe leading from the boiler to the discharge pipe, a valve situated within 85 said supply pipe, a drain pipe leading from said supply pipe on the boiler side of the supply pipe valve, a valve for regulating the drain pipe, a distributing pipe leading from each of the spring actuated valves, a plurality of branch pipes leading from the 90 distributing pipes and nozzles carried by the distributing pipes and situated at points opposite the ends of the flues to be cleaned.

3. In a boiler flue cleaner a discharge pipe 95 or header having a plurality of valves situated therein, means for supplying said discharge pipe with steam, a spring actuated valve stem carried by each of the valves, a grooved wheel carried by each of said stems, 100 a plurality of sheaves situated within the inclosing walls, a plurality of sheaves situated outside of the inclosing walls and at right angles to the first named sheaves, flexible cables secured to the grooved wheel and running over the sheaves, a series of pipes leading from each valve and a plurality of nozzles connected with each series of pipes and situated at points opposite the ends of the flues to be cleaned, whereby a portion 105 of the flues may be cleaned independent of the others.

In testimony whereof, I have hereunto affixed my signature in the presence of two subscribing witnesses.

RICHARD H. BATE, JR.
